UNITED STATES PATENT OFFICE.

LUCIEN LELONG, OF PARIS, FRANCE, ASSIGNOR TO LUCIEN LELONG, INC., OF NEW YORK, N. Y., A CORPORATION OF NEW YORK.

DESIGN FOR A BOTTLE.

Application filed April 12, 1928. Serial No. 26,303. Term of patent 7 years.

To all whom it may concern:

Be it known that I, LUCIEN LELONG, a citizen of the Republic of France, residing in the city of Paris, France, have invented a new, original, and ornamental Design for a Bottle, of which the following is a specification, reference being had to the accompanying drawing, forming a part thereof.

Fig. 1 is a front view of my design,
Fig. 2 is a side view, and
Fig. 3 is a top view thereof.

I claim:

The ornamental design for a bottle as shown.

LUCIEN LELONG.
